FRANK S. McDONNELL, OF MATTAPAN, MASSACHUSETTS, ASSIGNOR TO RICE, BARTON & FALES, INCORPORATED, OF WORCESTER, MASSACHUSETTS, A CORPORATION OF MASSACHUSETTS.

PAPER-MAKING MACHINE.

Application filed May 31, 1923. Serial No. 642,627.

To all whom it may concern:

Be it known that I, FRANK S. McDONNELL, a citizen of the United States, and a resident of Mattapan, Massachusetts, have invented new and useful Improvements in Paper-Making Machines, which invention is fully set forth in the following specification.

This invention relates to improvements in paper making machines, and more particularly to means for raising and lowering the suction boxes of such machines.

A paper making machine of the Fourdrinier type includes as parts thereof a plurality of suction boxes extending across the machine approximately parallel to each other and so positioned and secured in place that the endless making wire travels across the perforated covers of said boxes. The paper, or partly formed or finished paper, on the wire, is thus subjected to the suction of the boxes in succession, each box drawing from the paper, through the perforations in the cover of the box, a certain amount of the moisture in the paper. The ends of each box are positioned or extend beneath two parallel stationary side rails respectively of the machine frame and two long bolts with cap nuts are commonly used at each end of the box to secure the same in operative position to its stationary rail, said bolts passing upwardly through vertical openings in the end of the box and in the rail and being engaged above the rail by the cap nuts.

The suction boxes have to be quite frequently lowered from their operative position and removed endwise from the machine; this is necessary, for example, in replacing the making wire (sometimes called the Fourdrinier wire). To provide for such removal two parallel tracks are ordinarily provided extending across the machine beneath each suction box, and wheels on each box are adapted to be engaged with said tracks by the lowering of the box from its normal operative position, whereupon the box may be rolled endwise along its tracks out of the machine at one side thereof. The reverse of said procedure is followed in repositioning the box in the machine. Heretofore in lowering each suction box from its normal operative position secured to the stationary rails it has been necessary to gradually unscrew the cap nuts from the bolts with a wrench until the box rests on its underlying tracks.

A suction box is very heavy and while being lowered in the manner aforesaid its entire weight is on the bolts and nuts and the interengaging screw threads of the same. Therefore, the unscrewing of the nuts under such conditions to an extent to lower each suction box onto its tracks is a relatively slow and time consuming procedure. And in replacing the suction boxes it has heretofore been necessary to first start each nut on the end of its bolt and then gradually turn the nuts with a wrench causing the bolts to be drawn up and thereby lift the entire weight of the suction box until elevated to the rails and secured thereto in operative position. This also is a slow and time consuming procedure for the same reasons as stated with reference to the lowering of the boxes. As a paper making machine represents a considerable investment of money it is the effort to run such machines continuously and with as little interruption as possible in order to obtain therefrom quantity of product commensurate with the investment. Replacement of the Fourdrinier wire, which wears rapidly, is the main cause of interruption; and since replacement of a wire calls for removal of the suction boxes in order to get the old wire out and the new wire in, any saving of time in the process of removing and replacing the boxes becomes a factor in shortening idleness of the machine occasioned by each change of wire.

Generally the object of the present invention is the provision of means adapted to relieve the bolts and nuts, which secure a suction box in its normal operative position to the stationary rails, of the function of lowering the box to position for removal from the machine by endwise movement and also of the function of raising the box from such lowered position to its normal operative position, whereby said bolts and nuts may be both quickly removed and quickly replaced.

A further object is the provision of means adapted to support the suction box in approximately its operative position while said bolts and nuts are being removed; and further adapted to then quickly lower the suction box onto its tracks in position to be rolled out of the machine by endwise movement. A further object is to also utilize said means for lifting the suction box from its supporting tracks and supporting it

while the bolts and nuts which secure it to the stationary rails are being put in place. A still further object is the provision of quick-action means, such as cam levers and plungers actuated thereby (as contra-distinguished from slow-action screw-threaded means) for raising and lowering the suction box from and to position to be removed from the machine and for sustaining the suction box in elevated position while the bolts and nuts which secure it in that position to the stationary rails are being either put in place or removed.

The aforesaid and still other objects hereinafter set forth or apparent are accomplished by the now preferred embodiment of the invention illustrated in the accompanying drawing, wherein—

Fig. 1 is a vertical transverse sectional view through that portion of a paper making machine which includes the suction boxes, said view showing some parts only of the mechanism and frame-work;

Fig. 2 is an end elevation corresponding to Fig. 1 and showing only two suction boxes and their associated parts;

Fig. 3 is a detail view of one of the brackets;

Fig. 4 is a detail view of the cam end of a cam-lever; and

Fig. 5 is a detail view of one of the plungers which is actuated by a cam-lever.

Referring to the drawings, 10, 10, are two of a plurality of suction boxes such as constitute parts of a paper making machine and which may be, and are as shown, of well known construction, including a perforated cover 11, a pair of handles or grips 12, 12, at each end of the box, and two pairs of wheels or rollers at opposite ends respectively of the box, the wheels 13, 13, of one pair being journalled to one end of the box and positioned at opposite sides thereof, and the wheels 14, 14 of the other pair being similarly journalled and positioned at the other end of the box. As before stated, the making wire (not shown in the drawing) travels across and in engagement with the top surface of each perforated cover 11. The covers are commonly made of wood, particularly maple, about $1\frac{3}{4}$ inches thick and the perforations usually begin about six inches from each end of the cover. The travel of the wire thereover rapidly wears the contacted upper surface of the covers and hence it is customary to true said surfaces about once a week in ordinary running and more frequently if called for. These covers are also sometimes made of metal particularly bronze, and usually of a thickness varying from $\frac{5}{8}$ inch to one inch. By the lowering of a suction box from its normal operative position the rollers 13, 14 at one side thereof are adapted to engage an underlying track 15 carried by a beam 16,

while the rollers 13, 14 at the other side of the box are similarly adapted to engage an underlying track 17 carried by a beam 18. While this is the preferred arrangement of wheels and tracks, any other suitable arrangement thereof may be employed; for example, it has been heretofore proposed to journal wheels or rollers on the frame-work of the machine adapted to engage suitable track on the suction box upon lowering the latter from its operative position.

19 and 20 are rails positioned at opposite sides respectively of that portion of the Fourdrinier section of the machine which does not shake, as does the portion in advance of said rails. Hence said rails 19 and 20 are known as "stationary rails", in contrast to the rails in advance thereof which are vibrated or shaken. These stationary rails are usually made of steel encased in a covering of sheet brass and serve to carry other parts of the machine in addition to the suction boxes. As before stated, an ordinary suction box such as commonly used

is very heavy, one for a 200 inch width machine weighing approximately 1500 pounds, the weight increasing proportionately for greater widths of machine. As shown in Figs. 1 and 2, each suction box, when in normal operative position, is rigidly secured to and suspended from the stationary rails by long bolts and cap nuts. Thus two bolts 21, 21, pass upwardly through openings at one end of a box, through opening in the rail 19 above, and are engaged by cap nuts 22, 22 above said rail. Similarly arranged bolts 23, 23 with cap nuts 24, 24 support the other end of the box from the rail 20.

As before stated, it has heretofore been the practice with such structures to lower each suction box onto its tracks by gradually unscrewing the cap nuts 22, 22, 24, 24 with a wrench until the wheels or rollers 13, 13, 14, 14 engage the tracks 15 and 17, whereupon the bolts and nuts being relieved of the weight or load of the box, may be entirely removed to permit the box to be rolled endwise out of the machine. The unscrewing of the nuts under such conditions, with the weight or load of the box on the bolts, nuts and their interengaging screw threads, is necessarily a slow and time consuming operation and also imposes considerable strain and wear upon said screw threads. It has also been necessary heretofore to reverse said procedure in elevating each box from its tracks to its operative position in reassembling the boxes in the machine. In other words, the bolts and nuts and the unscrewing and screwing up of the nuts on their bolts, while sustaining the full load of the large weight of the suction box, have heretofore been relied upon as the only means of lowering the boxes to and raising them from the tracks.

The present invention provides means adapted to support the suction box in its elevated position while the nuts and bolts which secure it to the stationary rails are being loosened and removed, and to then lower the box onto its tracks for removal from the machine by endwise movement; said means being likewise adapted, in the replacement of the box to operative position, to lift the same from its tracks to juxtaposition with relation to the said supporting rails and to support the box in that position while the bolts and nuts are being again put in place and tightened to rigidly secure the box in operative position to said rails. As the bolts and nuts in this instance are not called upon to perform the office of lowering the suction box onto or raising it from its tracks, the unscrewing and removal of the nuts and bolts, and the replacement or screwing up of the same, may be easily and rapidly accomplished. The invention is capable of widely varying mechanical expressions, that now preferred being illustrated in the drawing.

30 and 31 are horizontal side beams of the machine frame located at opposite sides respectively of the machine approximately beneath the stationary rails 19 and 20 and serving particularly to support the means by which the positioning and removal of the suction boxes is accomplished. A peculiarly shaped bracket 32, preferably cast in one piece, is secured to beam 30 beneath one end of a suction box 10 by two bolts 33, 33, engaging through slots 34, 34 respectively of the bracket, said slots allowing some latitude of adjustment in positioning the bracket on the beam. The bracket is formed with two upright inwardly opening pockets 35 and 36 adapted to receive and support the two track beams 16 and 18 respectively at one end thereof. A similar bracket 32 is secured in a like manner to beam 31 and supports the track beams at their other end. Thus, for each suction box and its two track beams, there is a corresponding pair of brackets 32. Each of said brackets includes an inwardly extending arm 37 terminating in a head or sleeve 38 having therethrough an upright cylindrical bearing opening for a vertically operating plunger bar 39. A longitudinal groove in one side of said plunger is engaged by the inner end of a set screw 40 in an opening through the wall of sleeve 38, this arrangement permitting longitudinal up and down movement of the plunger in its sleeve while preventing rotary movement of said plunger. At its screw threaded upper end the plunger 39 is engaged by a nut or head 41 having a flat top surface adapted to contact a flat bottom surface at one end of the suction box, as most clearly shown in Fig. 1. At its lower end

plunger 39 is bifurcated forming a slot in which is journalled a small antifrictional wheel or roller 42. Beneath each plunger at each end of each suction box there is positioned a cam lever 43, and since these levers are all alike and each journalled in a similar bracket fastened to one or the other of the beams 30, 31, a description of one will suffice for all. 44 is a bracket fitting about the inner lower edge of the beam 30 and secured thereto by two horizontal bolts 45, 45, and a vertical bolt 46. Said bracket has two inwardly extending arms between which lever 43 is fulcrumed on a horizontal pivot pin 48 in position for its cam surface 47 to engage the antifrictional wheel 42 of the corresponding plunger. It has been found desirable to position the suction boxes close together so as to make them act as nearly as possible as one complete suction box, and this sometimes occasions irregularity in the relative positioning of the boxes because of other conditions of construction encountered. Thus it may happen that provisions made for locating brackets 44 and their corresponding brackets 32 would not (without change) locate said brackets always in the same relative positions one above the other. To give some latitude for irregularity of such relative positioning and to save the effort and expense of precise relative positioning, the cam surface 47 of each cam lever is quite wide, and the wheel 42 of the plunger may engage said surface near the middle thereof or near either end thereof, as shown in dotted lines Fig. 2.

In the position of the parts shown in Fig. 1, the cam levers 43 have elevated the plungers 42, 42, with the top surfaces of the heads 41, 41, of said plungers in engagement with the bottom surface of the box at opposite ends thereof respectively; and the box has been rigidly secured to the stationary rails 19 and 20 by the bolts 21 and their nuts 22, and bolts 23 and their nuts 24, the nuts being tightly turned up on the bolts and perforated cover 11 of the box being clamped at its opposite ends between the bottom surfaces of the rails 19 and 20 respectively and the top surface of the edge of the box. As before stated, the wear on the top surface of the cover 11 requires frequent truing thereof and each such truing slightly reduces the thickness of the cover to be clamped between the rails 19, 20 and the top surface of the edge of the box. To compensate for such diminutions of the thickness of the cover and insure proper functioning of the levers and the plungers in lifting the suction box to the full extent desired—that is, until the top surface of the cover contacts the under surfaces of the rails 19 and 20—the plungers are made extensible by rotation of their heads or nuts

- 41 in screw thread engagement with the main body of the plungers; in other words the plungers can be readily adjusted to the exact length desired.
- 5 To remove a box from its operative position in the machine, for example the box 10 shown in Fig. 1, the nuts 22 and 24 are first loosened by a slight turn with a wrench, whereupon the nuts may be rapidly spun 10 off their bolts by hand if desired, the suction box being in the meantime supported by the cam-levers and their plungers. After the nuts and bolts have been completely removed, the cam levers 43, 43 are swung 15 outward at their lower ends, lowering the plungers and with them the suction box until the wheels of the latter engage the tracks 15 and 17 and deliver the weight of the box onto said tracks. The suction box may 20 then be rolled out of the machine by endwise movement along its tracks. The reverse of said procedure is followed in replacing the suction box in operative position in the machine. After the suction box has been rolled 25 along its tracks to proper position under the stationary rails, the cam-levers 43, 43 are moved downward to the vertical positions in which they are shown in Fig. 1, thereby actuating the plungers to lift the 30 suction box off its tracks to the position in which the top surface of its cover 11 engages the bottom surfaces of the rails 19 and 20. The bolts 21 and 23 are then inserted upward through their holes, the cap 35 nuts 23, 24 engaged with the upper ends of the bolts and after being rapidly spun into position are finally tightened or set by a wrench to thereby rigidly secure the suction box to the rails.
- 40 What I claim as new is:—
1. In a paper making machine, the combination of a suction box; means by which said suction box is supported in operative position; means detachably securing said 45 suction box to its said supporting means; means onto which said suction box is adapted to be lowered from its said operative position and by which said box is adapted to be supported while being moved endwise in 50 removing it from and replacing it in the machine; and other means operable to raise and lower said box from and to its said lowered position to and from its approximate operative position and to support said 55 box in said last-named position while said securing means are being applied or removed.
2. In a paper making machine, the combination of a suction box; means by which 60 said suction box is supported in operative position; means detachably securing said suction box to its said supporting means; means onto which said suction box is adapted to be lowered from its said operative position and by which said box is adapted to be 65 supported while being moved endwise in removing it from and replacing it in the machine; and other means operable to raise and lower said box from and to said track to and from the approximate operative position of said box when secured to said stationary rails and to support said box in its 70 said approximate operative position while said securing means are being applied or removed.

supported while being moved endwise in removing it from and replacing it in the machine; and other means operable to raise and lower said box from and to its said lowered position to and from its approximate operative position and to support said box in said last-named position while said securing means are being applied or removed, said raising and lowering means including a lever movable to one position to lower said suction box and to another position to raise it.

3. In a paper making machine, the combination of a suction box; stationary rails at opposite ends of said suction box; means detachably securing said suction box to said stationary rails in operative position; track onto which said suction box is adapted to be lowered from its said operative position and by which said box is adapted to be supported while being moved endwise in removing it from and replacing it in the machine; and lever actuated means at each end of the box operable to raise and lower said box from and to said track to and from the position in which it is secured to said stationary rails and to support said box in said last named position while said securing means are being applied or removed.

4. In a paper making machine, the combination of a suction box; stationary rails at opposite ends of said suction box; means detachably securing said suction box to said stationary rails in operative position; track onto which said suction box is adapted to be lowered from its said operative position and by which said box is adapted to be supported while being moved endwise in removing it from and replacing it in the machine; and other means operable to raise and lower said box from and to said track to and from the approximate operative position of said box when secured to said stationary rails and to support said box in its 105 said approximate operative position while said securing means are being applied or removed.

5. In a paper making machine, the combination of a suction box; stationary rails at opposite ends of said suction box; means detachably securing said suction box to said stationary rails in operative position; track onto which said suction box is adapted to be lowered from its said operative position and by which said box is adapted to be supported while being moved endwise in removing it from and replacing it in the machine; and other means operable to raise and lower said box from and to said track to and from the approximate operative position of said box when secured to said stationary rails and to support said box in its 120 said approximate operative position while said securing means are being applied or removed.

moved, said means including a lever the swinging of which on its fulcrum to one position lifts the suction box and to another position lowers said box.

5 6. In a paper making machine, the combination of a suction box; stationary rails at opposite ends of said suction box; bolts passing upward through openings in the ends of said suction box and in the stationary rails to suspend the box from and secure it to said rails in operative position; track onto which said suction box is adapted to be lowered and by which said box is adapted to be supported while being moved endwise in removing it from and replacing it in the machine; and other means operable to raise and lower said box from and to said track to and from the approximate operative position of said box

10 15 20 when secured to said stationary rails and to support said box in its said approximate operative position while said bolts and nuts are being applied or removed.

7. In a paper making machine, the combination of a suction box; stationary rails at opposite ends of said suction box; bolts passing upward through openings in the ends of said suction box and in the stationary rails to suspend the box from and secure it to said rails in operative position, track onto which said suction box is adapted to be lowered and by which said box is adapted to be supported while being moved endwise in removing it from and replacing it in the machine; and other means operable to raise and lower said box from and to said track to and from the approximate operative position of said box when secured to said stationary rails and to support said box in its said approximate operative position while said bolts and nuts are being applied or removed, said means including a lever the swinging of which on its fulcrum to one position lifts the suction box and to another position lowers said box.

8. In a paper making machine, the combination of a suction box, a stationary rail at one end of said suction box, one or more bolts passing upward through openings in the end of said suction box and in said stationary rail each bolt being engaged by a nut at its upper end above said rail to suspend the end of the box from and secure it to said rail in operative position, track positioned below and onto which said suction box is adapted to be lowered and by which said box is adapted to be supported while being moved endwise in removing it from and replacing it in the machine, and other means operable to raise and lower said end of the box from and to said track to and from the approximate operative position of said box when secured to said stationary rails and to support said box in its said approximate operative position while said bolts and nuts are being applied or removed, said means including a plunger movable up and down at each end of the box and a cam-lever for actuating each of said plungers.

operative position while said bolts and nuts are being applied or removed, said means including a plunger movable up and down in engagement with the box and a cam-lever actuating said plunger.

9. In a paper making machine, the combination of a suction box, a stationary rail at one end of said suction box, one or more bolts passing upward through openings in the end of said suction box and in said stationary rail each bolt being engaged by a nut at its upper end above said rail to suspend the end of the box from and secure it to said rail in operative position, track positioned below and onto which said suction box is adapted to be lowered and by which said box is adapted to be supported while being moved endwise in removing it from and replacing it in the machine, and other means—other than said bolts and nuts—operable to raise and lower said end of the box from and to said track to and from the approximate operative position of said box when secured to said stationary rails and to support said box in its said approximate operative position while said bolts and nuts are being applied or removed, said means including a plunger movable up and down, a head screw threaded onto the upper end of said plunger and adapted to engage said box, and a cam lever the cam surface of which engages the lower end of said plunger.

10. In a paper making machine, the combination of a suction box; stationary rails at opposite ends of said suction box; bolts passing upward through openings in the ends of said suction box and in the stationary rails said bolts being engaged by nuts at their upper ends above said rails to suspend the box from and secure it to said rails in operative position; track onto which said suction box is adapted to be lowered and by which said box is adapted to be supported while being moved endwise in removing it from and replacing it in the machine; and other means operable to raise and lower said box from and to said track to and from the approximate operative position of said box when secured to said stationary rails and to support said box in its said approximate operative position while said bolts and nuts are being applied or removed, said means including a plunger movable up and down at each end of the box and a cam-lever for actuating each of said plungers.

11. In a paper making machine, the combination of a suction box; stationary rails at opposite ends of said suction box; bolts passing upward through openings in the ends of said suction box and in the stationary rails said bolts being engaged by nuts at their upper ends above said rails to suspend the box from and secure it to said

rails in operative position; track onto which said suction box is adapted to be lowered and by which said box is adapted to be supported while being moved endwise in 5 removing it from and replacing it in the machine; and other means operable to raise and lower said box from and to said track to and from the approximate operative position of said box when secured to said 10 stationary rails and to support said box in its said approximate operative position while said bolts and nuts are being applied or removed, said means including at each end of the suction box a plunger movable up and 15 down and adapted to engage said box and a cam-lever the cam surface of which engages the lower end of said plunger.

12. In a paper making machine, the combination of a suction box; stationary rails 20 at opposite ends of said suction box; bolts passing upward through openings in the ends of said suction box and in the stationary rails said bolts being engaged by nuts at their upper ends above said rails to suspend 25 the box from and secure it to said rails in operative position; track onto which said suction box is adapted to be lowered and by which said box is adapted to be supported while being moved endwise in removing it 30 from and replacing it in the machine; and

other means operable to raise and lower said box from and to said track to and from the approximate operative position of said box when secured to said stationary rails and to support said box in its said approximate 35 operative position while said bolts and nuts are being applied or removed, said means including at each end of the suction box, a plunger movable up and down, a head screw threaded onto the upper end of said plunger and adapted to engage said suction box in supporting the same, and a cam-lever the cam surface of which engages the lower end of said plunger.

13. In a paper making machine, the combination of a suction box adapted to be operatively positioned in the machine at one elevation and to be moved to another elevation for removal from the machine; means by which said suction box is supported in 45 its operative position; means detachably securing said suction box when in operative position to its said supporting means; and quick-action means operable to raise or lower said suction box from one of said 50 positions to the other.

In testimony whereof I have signed this specification.

FRANK S. McDONNELL.
